MOLD OPERATING MECHANISM FOR
GLASSWARE FORMING MACHINES

Frank O'Neill, Miami Beach, Fla., assignor to
Hartford-Empire Company, Hartford, Conn.,
a corporation of Delaware

Original application August 30, 1935, Serial No.
38,569. Divided and this application April 22,
1937, Serial No. 138,283

4 Claims. (Cl. 49—42)

My present invention relates to mold operating mechanism for glassware forming machines and specifically to means for opening and closing a mold of such a machine and for securing that mold in closed position under sufficient pressure to oppose any pressure applied internally thereof in forming glass therein. The present case is a division of my prior and copending application, Serial No. 38,569, filed August 30, 1935, and entitled "Glassware forming machine" now Patent No. 2,111,296 granted March 15, 1938.

Among the objects of the present invention are to provide novel means for opening and closing either a blank or a finishing mold of a glassware forming machine in such manner that the mold to which my novel opening and closing means are applied may be securely held closed during the forming of glass therein.

Further objects of the present invention will be in part apparent and in part pointed out hereinafter.

In the drawings:

Figure 1 is a view principally in vertical section and with parts in elevation illustrating the application of my novel mold operating means to a rotary type glassware forming machine; and

Figs. 2, 3 and 4 are views principally in horizontal section on the line A—B of Fig. 1 illustrating different positions of the mold opening and closing means; Fig. 2 illustrating the mold closed and locked; Fig. 3, the mold closed but not locked; and Fig. 4, the mold open.

I contemplate that the mold operating means forming the subject matter of the present invention may be applied to many different types of glassware forming machines, including those in which the molds are relatively stationary and also those in which the molds are moved as in rotary type machines, now in common use in the art, in which the molds are rotated about a vertical axis. Further, my present invention may be applied to rotary machines either of the single or multiple table types, and also to such machines, whether the molds be rotated continuously or intermittently. I have, however, chosen for the purposes of the present case to illustrate my novel mold operating mechanism applied to a continuously rotating machine of the two-table type, such as that forming the subject matter of my parent application above referred to, the particular application of the invention here specifically illustrated and described being to the operation of the blank molds of that machine. It will be in part apparent and in part pointed out hereinafter, however, the manner in which

the invention may be applied to the blow molds of such a machine, or to blank or blow molds of other types of machines.

Referring to Fig. 1 of the present drawings, there is illustrated a portion of the blank mold carrier of a glassware forming machine comprising a blank mold table which is mounted for continuous rotation upon a central column 35. The rotatable portions of the blank mold table comprise a lower spider 36 an upper spider 37 and an intermediate spider 38, which are suitably connected together so that they may rotate as a unit about said central column. A ring gear 39 encircles and is integrally formed with the lower spider 36, said gear being operatively connected to driving mechanism in a manner not illustrated in the present drawings, but disclosed fully in my parent application above referred to. The machine includes a plurality of blank mold units 33 mounted upon the intermediate spider 38 in such fashion that they may be rotated in respect thereto in intermittent steps, each of an angle of 180°, and thereby alternately inverted and reverted.

Each mold unit 33 includes a portable body 25 mold 40 connected by arms 41 to a hinge pin 42 and a portable neck mold 43, which is carried by a pair of arms 44, the latter being pivoted to the aforesaid hinge pin 42. This hinge pin 42, which forms a part of a turn-over unit, is permanently mounted on a head 45, which is connected to the outer end of a sleeve 46, the latter being journaled in a horizontal bearing 47, the axis of which extends radially of the mold table in the machine illustrated in Fig. 1. A circular flange 35 48 extending radially outward from the outer end of the sleeve 46 in proximity to the inner end of the head 45 carries an annular series of rollers 49, which are intended for engagement with notches 50 or recesses provided in the lower surface of an arcuate plate 51, said plate being suitably secured to a cam carrier 52. This cam carrier is keyed to the central column 35, as will be seen in Fig. 1, and supports cams for controlling the opening and closing of the blank and neck molds as well as devices for locking the turn-over units in either of their two operating positions.

The turn-over unit is adapted to be locked in either of its two operating positions by means including a pair of diametrically opposed notches 53 or recesses in the periphery of the flange 48 and a suitable detent (not shown herein), which is adapted to move vertically within a casing 55 and to be actuated for vertical movement by a 55

lever 58, which is pivoted at 59 to a bracket depending from the upper spider 37. At its inner end, the lever 58 carries a cam roller 62 arranged to be engaged by a cam 63. The connection between the lever 58 and the detent within the sleeve 55 is such as to provide for certain necessary lost motion. In operation, when the lever 58 is moved sufficiently in a counterclockwise direction, as seen in Fig. 1, about its pivot 59, by the cam 63, the detent will be withdrawn from the adjacent notch 53 to permit inversion of the turn-over unit. When the lever 58 is moved from its extreme counterclockwise position, the detent will be spring pressed into engagement with one or the other of the notches 53.

The body blank mold 40 is opened and closed independently of the neck mold by mechanism, which for the greater part is disposed within the sleeve 46. This mechanism includes a yoke 64 spaced inwardly from the corresponding blank mold and connected to the body mold sections by means of levers 65, which are pivoted intermediate their ends to the yoke by vertical hinge pins 66. The outer end of each lever is pivoted to the adjacent mold arm 41. A push rod 68 is threaded into or otherwise secured to the yoke 64, said rod extending axially through the sleeve 46 and being slidably connected at its inner end to a slide block 69, which carries a cam roll 70 operatively engaged with a stationary cam 71, the latter carried by a hub 72 keyed to the central column 35. A coil spring 73, encircling the rod 68 and bearing at its outer end against a collar 74 and at its inner end against a sleeve-like extension 75 on the block 69, yieldingly holds the yoke 64 and the slide block 69 in their maximum spaced relation and provides operating connection between them.

Arranged in proximity to the inner side of the yoke 64 is a spreader 76, which is mounted for sliding movement in the direction of the length of the rod 68 and operated to impart additional mold closing pressure to the levers 65 to lock the mold in closed position. This is accomplished by providing for engagement between cam surfaces 71 on the spreader 76 and similar surfaces on the inward extensions 78 of the levers 65. The spreader 76 is suitably secured to the outer end of a sleeve 79, which partially encloses the push rod 68 and completely encloses the coil spring 73, this sleeve telescoping over the tubular extension 75 on the slide block 69. The outer end 80 of the sleeve 79 is reduced in diameter to provide an annular shoulder 81 against which a coil spring 82 abuts, the opposite end of this spring engaging the outer end of the tubular extension 75.

Thus, it will be seen that radial outward movement of the cam roller 70 operates through the two coil springs 73 and 82 and the yoke 64 and levers 65 to close the body blank mold 40; and that after a predetermined extent of movement on the part of the yoke 64, the spreader 76 begins to function, and by applying added closing pressure to the arms 41, serves securely to hold the body blank mold 40 against premature opening and to lock that mold against any pressure which may be applied internally in forming glass in the mold.

Guide rods 83 connect the head 45 and a plate 84, which is secured to the inner end of the sleeve 46, said rods extending through diametrically disposed recesses, seen in dotted lines only in Fig. 1, in the periphery of the spreader 76, whereby in-

version and reversion of the blank mold unit correspondingly moves the push rod 68 and other elements associated therewith, excepting only the slide block 69 and the cam roll 70. These two elements are prevented from rotation by mounting them for translatory sliding movement only in a suitable guide means 69a, which is secured to the intermediate spider 38. A plate 86 closes the inner end of the bearing 47.

It will be understood that when the principles of the opening and closing mechanism, just described for an invertible blank mold, are applied either to a non-invertible blank mold or to a blow mold, which is usually non-invertible, some simplification may be made, as will be obvious to those skilled in the art, as there need be no relative rotational movement between the slide block 69 and the other parts of the device operated thereby including the spreader 76 and the push rod 68. There should, however, be a relative sliding movement permitted between these parts, so that they cannot be rigidly secured together, but should be spaced apart by the compression springs 73 and 82.

The operation of the machine illustrated in part in Fig. 1, and more particularly forming subject matter of my parent case, is not described fully herein, but references may be had to my above-identified parent case for a full and complete description if desired. In general, however, suitable means, not shown in detail, are provided for independently opening and closing the neck ring, including an end portion 94 for the lever 58, which is arranged to engage the end of a push rod 90 when the mold unit 33 is reverted to a neck-up position to actuate a suitable wedge and thereby to open the neck ring against a spring (not shown).

In forming a blank or parison in the blank forming unit 33, the charge is supplied through the open end of the blank mold 40 at a time when the baffle shown at 142 is above and laterally out of line with this mold, the charge preferably being supplied from a suitable automatic feeder in a manner now well known in the art. A suitable neck pin (not shown) is provided in association with the neck ring 43 and the charge may be settled either by suction transmitted to the region around the neck pin through a pipe 111 and suitable associated passages or by pressure supplied through the upper end of the blank mold, or both. Counterblowing operations may be carried on in a conventional manner, or in the particular manner illustrated in my said parent case. Inasmuch, however, as the process of forming parisons forms per se no part of the present invention, it is not fully illustrated herein and will not be further described.

Subsequent to the complete formation of the parison in the blank forming unit 33, it may be transferred by suitable means to a final blow mold, which in the parent case is mounted on an adjacent rotary table, and there expanded to final form. Here again, the particular means for transferring and final blowing the parisons form no necessary part of the present invention and are not illustrated. These operations may be carried on in the manner fully disclosed in my parent application, or in any other desired manner, including those known to the art.

While I have shown and described but one embodiment of my invention, it will be understood that the principles thereof may be applied in many different ways, and certain features may

be used independently of others. I do not wish to be limited, therefore, except by the scope of the appended claims, which are to be construed as broadly as the state of the prior art permits.

5 I claim:

1. In a glassware forming machine, a mold comprising a pair of cooperating sections pivoted to a common hinge pin, a pair of levers connected to said mold sections and pivoted to separate hinge pins disposed parallel to the first named hinge pin, a yoke connecting said separate hinge pins, means for moving said yoke in a fashion alternately to open and close the mold, and a device operable by the yoke moving means for applying additional closing pressure to said levers, said device including extensions carried by said levers and a spreader movable into and out of engagement with said extensions.

2. In a glassware forming machine, a mold comprising a pair of cooperating sections pivoted to a common hinge pin, a pair of levers connected to said mold sections and pivoted to separate hinge pins disposed parallel to the first named hinge pin, a yoke connecting said separate hinge pins, a push rod connected to said yoke, cam means for actuating said rod and thereby alternately opening and closing the mold, and means for applying closing pressure to the mold in addition to that necessary to close the mold including

extensions on said levers and a spreader actuated by said cam means and thereby brought into operative engagement with said extensions.

3. In combination, a mold comprising a pair of sections pivoted to a common vertical hinge pin, a yoke, a pair of levers pivoted substantially midway their lengths to the ends of said yoke, means connecting one end of each of the levers to the mold sections, means for moving the yoke and levers to close the mold, and means adapted 5 yieldingly to engage the other ends of said levers and thereby apply pressure to the mold sections beyond that necessary initially to close the mold.

4. In combination, a mold comprising a pair of sections pivoted to a common vertical hinge pin, a 10 yoke, a pair of levers pivoted substantially midway their lengths to the ends of said yoke, means connecting one end of each of the levers to the mold sections, means for moving the yoke and levers to close the mold, and means adapted 15 yieldingly to engage the other ends of said levers and thereby to apply pressure to the mold sections beyond that necessary initially to close the mold, said last named means including a spreader, cam means primarily operating to move said 20 yoke and levers in closing the mold and a yielding operative connection between said spreader and said cam means. 25

FRANK O'NEILL.
